DESIGN FOR A BALL POINTED FOUNTAIN
PEN OR SIMILAR ARTICLE

Jack Pearl, Kew Gardens, N. Y., assignor to Rich-Marc Mfg. Co., Inc., New York, N. Y., a corporation of New York

Application October 16, 1947, Serial No. 141,959

Term of patent 14 years

(Cl. D74—17)

To all whom it may concern:

Be it known that I, Jack Pearl, a citizen of the United States of America, and a resident of Kew Gardens, in the county of Queens, city and State of New York, have invented a new, original, and ornamental Design for a Ball Pointed Fountain Pen or Similar Article, of which the following is a specification, reference being had to the accompanying drawings, forming a part thereof.

In these drawings:

Figure 1 is a side elevational view of a ball pointed fountain pen, showing my new design; and

Figure 2 is an end elevational view of the same.

I claim:

The ornamental design for a ball pointed fountain pen, or similar article as shown.

JACK PEARL.
